UNITED STATES PATENT OFFICE

2,505,721

MANUALLY OPERATED ADJUSTABLE
OAR WHEEL

Gustave C. Peter and Francis J. Schmidt, Wauwatosa, Wis., assignors to The Peter-Schmidt Corporation, Chicago, Ill., a corporation of Illinois

Application December 3, 1945, Serial No. 632,326

19 Claims. (Cl. 115—23)

1

This invention relates to a propelling mechanism for small water craft such as rowboats and the like although it may have a more general use wherever applicable.

An important object of the invention is to provide a boat propeller of the rotary oar type which comprises a plurality of oar members demountably secured to a supporting hub which is rotated by a manual operator from within the boat.

A further object of the invention is to provide a boat propelling mechanism which may be easily attached to or detached from any small craft of the rowboat type, the parts being so connected and assembled that the oar mechanism may be moved from a vertical wheel position at the outside of the boat to an inverted position within the boat where the blades and the wheel mechanism are accessible for removal, repair and replacement.

A further object of the invention is to provide a rotary oar construction in which an oar wheel is mounted for vertically adjustable movement and also may be swung at various angles in an upright plane.

Still a further object of the invention is to provide a removable and adjustable splash shield which overlies a portion of the path of the oar wheel and is selectively movable in a variety of angular positions over the path of the wheel.

A number of other objects and advantages which are inherent in this type of boat propeller will appear in the specification and are apparent from the accompanying drawings in which,

Fig. 1 is a side view of a small boat with a rotary oar construction in accordance with this invention applied at the side thereof;

Fig. 2 is a side elevation of the rotary oar as shown in Fig. 1 but viewed from the opposite, inner or clamping side of the structure;

Fig. 3 is an enlarged sectional view showing the mounting of the splash shield as taken on the line 3—3 of Fig. 2;

Fig. 4 is a vertical sectional view of the oar construction as shown in Fig. 2 and with the clamp applied to a boat gunwale;

Fig. 5 is a view of the wheel driving mechanism as taken on the line 5—5 of Fig. 4; and

Fig. 6 is an end view of the blade clamping mechanism as taken on the line 6—6 of Fig. 4.

In the oar wheel type of small boat propellers, the constructions heretofore used have either been permanently applied to the water craft or they are so large and cumbersome that they are neither adapted for free or easy detachment from and connection to various boats nor are

2

they composed of parts which are easily disassembled or taken apart to occupy a small space in transporting them from one place to another, and for readily setting them up on another boat.

5 The present invention overcomes all of these difficulties by making the blades removable from a hub, by mounting the wheel for vertical and angular adjustment and for swinging the wheel from a rowing position to an inverted position within the boat, and providing a splash shield which is adjustable with respect to the wheel and may be easily removed for compactness in packing.

Referring now more particularly to the drawings, an oar wheel hanger 10 and a support 11 are pivoted together by means of a sleeve 12 which projects from one side of the support to form a hub upon which the hanger is mounted and projects at the other side of the support

10 where it is strengthened by ribs 13 connected thereto. Within the sleeve 12 are bushings 14 for mounting a crank shaft 15 freely therein, one end of the crank shaft projecting beyond the hanger 10 to provide a support for a driving pulley 16 connected thereto by a key 17, and the other end of the shaft projecting beyond the end of the sleeve 12 and having a handled crank 18 for manually rotating the shaft and pulley wheel 16.

15 In the upper edge of the support 11 are a plurality of notches 19 for engaging a trigger 20 pivoted in a projection 21 extending from the top of the hanger 10 over and beyond the upper end of the support 11, and the trigger being pressed

20 into engagement with any selected one of the notches 19 by a spring 22 interposed between the back of the trigger and the adjacent extending portion 21. To vary the position of the hanger with respect to the support, it is necessary only

25 to press upwardly on the trigger and to move the hanger in either direction allowing the trigger to engage any one of the other notches. Just beyond the two outermost notches 19 are projections 23 extending outwardly from the support 11

30 and adapted to engage a stop projection 24 extending downwardly from the trigger adjacent the support. The engagement of the projection 24 with the stop projections 23 limits the relative movement of the hanger and support.

35 To mount the support upon a boat, a gunwale clamp is provided which comprises a U-shaped clamp member 25 adapted to fit freely over a gunwale 26 of considerable width. The clamp member has upstanding ears 27 at its inner ends adapted to be pivoted in corresponding ears 28

3

at the bottom of the support 11 which are spaced outwardly therefrom by a connecting web 29. The ears 27 and 28 are preferably connected by a common pivot 30 so that the support will swing freely with respect to the clamp member locating the lower end of the hanger 10 at the outer side of the clamp.

In order to adjustably position and connect the support 11 with respect to the clamping member the latter is also provided with projections 31 opposite the ears 27, each having a slot 32 for receiving a common cross bolt 33 extending through the hanger 10 at the angle of its connection with the web 29 parallel to the pivot 30, and having an adjustable wing nut 34 at one end by means of which it may be tightened and loosened with respect to the slotted projections 31. With this construction the support 11 may be raised and lowered with respect to the gunwale clamp or if desired disengaged entirely therefrom, swinging the support inwardly upon the pivot 30 so that the support and the hanger may be disposed within the boat.

Any suitable clamping means may be provided in connection with the clamp member 25 but preferably a clamping screw 35 is inserted through each end of the clamp member having an attached contact member 36 at its inner end to engage the inside of the edge of a boat, or the gunwale thereof and having a handle 37 attached at the outer end of the clamp screw for applying and removing it.

Mounted at the lower end of the hanger 10 is an oar wheel shaft 38 projecting outwardly therefrom and having an oar wheel hub 39 mounted thereon by means of bushings 40. The hub is freely rotatable upon the shaft and has an outwardly extending threaded sleeve portion 41 engaged at its outer end by a washer 42, with a cotter pin 43 extending through the shaft for holding the washer in place. The shaft is drawn up at its other end by means of a washer 44 which engages the hanger 10 around the shaft and by a stud bolt 45 inserted into this end of the shaft 38 and drawn up tightly against the washer 44. With this construction the wheel hub 39 is mounted for rotation upon the shaft and is provided with a belt groove 46 in line with the corresponding groove of the pulley 16 and connected to the pulley by a driving belt 47. Between the wheel hub and the pulley a belt tightener may be inserted comprising an idler pulley 48 mounted upon a slide 49 having a slot 50 therein through which a thumb screw 51 extends into the adjacent portion of the hanger 10 so that the pulley may be advanced and withdrawn to variably engage the belt 47 for tightening or loosening it.

The oar wheel comprises the hub 39, a clamping plate 52 movable upon the sleeve portion 41 of the hub, a threaded clamping thumb screw 53 and a plurality of oar blades 54. Each oar blade is thin and flat, preferably made of metal, rounded at the outer and inner ends with one side terminating in a thicker and reinforcing shank 54a which is off-center with respect to the blade. Each shank has a projection 55 near its free end and the clamping plate 52 has corresponding recesses 56 to receive the projections 55 of the different shanks, the hub 39 and the clamping member 52 being each formed with complementary recesses 57 and 58 in which the ends of the shanks 54a are received and seated with the projections 55 engaging in the recesses 56 of the clamping plate, so that when the clamping plate is tightened against the oar shanks they will be

4

tightly engaged and seated and will be prevented from relative rotative movement in the mounting hub. The washer 42 blocks movement of the thumb screw 53 axially off of the sleeve 41. For convenience the thumb screw 53 which is movable on the threaded end of the sleeve 41 is preferably attached to the clamping member by a plurality of fastening clips 59 secured to the clamping member 52 and movable with it, so that the movement of the clamping screw upon the threaded hub sleeve produces a corresponding movement of the clamping plate 52. With this construction the oars may be easily attached to the hub and removed therefrom without removing the clamping plate or its adjusting screw from the wheel hub.

Extending over the path of the blades of the oar wheel for a portion of their periphery is a spray shield 60 preferably covering slightly more than one-quarter of the path of the blades and extending from opposite sides of the hanger member 10 downwardly therefrom with a trailing rear portion 61, the lower edge of the shield being approximately in a horizontal plane at the level of the lower portion of the hanger just above the shaft 38.

The shield is removably mounted upon the hanger 10 by providing a slot 62 extending vertically at its front end from the lower edge thereof, adapting it to be seated in guide grooves 63 in opposite edges of the hanger member 10, whereby the shield may be inserted from the top downwardly upon the hanger member 10 with the upper flaring edge disposed outwardly and downwardly from the hanger member 10, so that as the hanger member is swung forwardly or rearwardly with respect to the support 11, the spray shield will be carried therewith, rotating the spray shield accordingly.

With this construction the oars may be relatively raised or lowered, and advanced forwardly or rearwardly by adjusting the position of the hanger 10 relative to the support; the support and the hanger may be adjusted in vertical position with respect to the clamp by swinging the support upon its pivot 30 and by locking the support in any adjusted position by means of the clamping bolt 33. This latter construction is particularly useful in lifting the oars, as when near shore, in shallow water, or to swing the entire mechanism into the boat quickly when approaching a pier or any other obstruction which might damage it.

By having the parts quickly detachable and easily disassembled, the entire construction may be taken apart and stored or packed compactly for shipping or transporting it from one location to another. If any repair or adjustment is necessary while the mechanism is in operation either oar wheel may be quickly withdrawn from the water and overturned into the boat where the entire wheel mechanism is freely accessible for repair and replacement.

While we have described a preferred construction by way of illustration and not of limitation, it is apparent that various changes in the construction, combination and arrangement of the parts may be made without departing from the spirit and scope of the invention.

We claim:

1. A rotary oar comprising, a gunwale clamp, a support to extend upwardly therefrom, a shaft extending transversely in the support, a hanger mounted on said shaft and extending downwardly below the support outside a gunwale, a second

shaft at the lower end of the hanger parallel to the shaft in the support, an oar holder mounted on said second shaft, means to rotate the holder from the support shaft, and a plurality of oars each having a blade portion with a shank portion at one side thereof mounted in said holder so the blade portion will extend outwardly from the hanger and will swing downwardly below the hanger as the holder is rotated.

2. A rotatable oar wheel for boats comprising a hub rotatable about a horizontal axis above the water line, a plurality of oars extending radially from the hub and adapted to be rotated therewith with the blades of the oars successively submerged in part within the water, a shaft whereon the hub is mounted for rotation, and whereby the position of the oar wheel relative to the water line is fixed, a hanger for the shaft pivotally supported remote from its lower end whereat the shaft is carried, means for securing the hanger in a selected adjusted position relative to its pivotal support whereby to vary the vertical position of the shaft at its lower end and raise or lower the position of the oar wheel relative to the water line, a manual operator rotatable coaxially with the pivotal support for the hanger, and means for transmitting motion from the manual operator to the hub whereby to rotate the hub and oars carried thereby.

3. In a portable knock-down rotary oar, an oar wheel comprising a plurality of oar blades, a clamping hub in which the oar blades are removably mounted, a hanger for supporting the hub at one end thereof, a support to which the hanger is pivotally connected at a distance from the hub, a manual operator comprising a crank extending through the connection between the hanger and the support, a splash shield having a removable sliding engagement with the hanger, means for selectively locking the hanger in a variety of angular positions relative to the support, a gunwale clamp pivoted to the support, and an adjustable fastening connection between the clamp and the support by means of which the support may be adjusted relative to the clamp in various angular positions and also swing free from said fastening connection to hinge the support and the wheel parts connected therewith inwardly from a rowing position to a position within a boat.

4. For use on a boat, in combination, an oar wheel, a pivotally adjustable mounting for the oar wheel, and coaxially of said mounting a manual operator for rotating the wheel in any adjusted position upon its pivotal mounting, a laterally pivotally adjustable means for supporting the pivotally adjustable mounting, and a gunwale clamp whereby the laterally adjustable means is carried.

5. For use with a boat, a rotary oar comprising an oar wheel, a mounting for the oar wheel pivotally adjustable for and aft of the boat and, coaxially of said mounting, a manual operator for rotating the wheel in any adjusted position, means for detachably securing the oar wheel and its mounting to the boat gunwale and a spray shield carried by the adjustable mounting to the outside of the oar wheel and movable as a unit with the mounting to remain in a fixed position relative to the oar wheel in all adjusted positions of the mounting.

6. For use with a boat, an oar wheel, a mounting for the oar wheel adjustable fore and aft of the boat, a support upon which the mounting is adjustably carried, and a shield for the oar wheel

slidably engaged with the mounting in a manner to be supported in all adjusted positions thereof but in a single position which is fixed relative to the oar wheel.

5. For use with a boat, an oar wheel, a mounting for the oar wheel adjustable fore and aft of the boat, a support on which the mounting is pivotally adjustable about an axis longitudinally of the boat, means for adjusting the angular position of the mounting with respect to the support, and a spray shield for the oar wheel carried by the mounting and adjustable therewith into various positions relative to the support but always in a fixed position relative to the oar wheel.

10. In a rotary oar, a gunwale clamp, supporting means mounted on the clamp, a plurality of oar blades each having an off-center mounting shank with a projection therefrom, a blade holder supported by said means and comprising separable clamp parts one of which has recesses to engage said projections of the shanks to prevent rotation thereof, and means for rotating the blade holder.

15. In a rotary oar, a plurality of blades each having an off-center shank with means extending laterally therefrom, a blade holder comprising relatively movable parts and means for clamping them together, and at least one of the parts having recesses to engage the laterally extending means for holding the oar shanks against turning in the holder.

20. In a rotary oar, a plurality of blades each having an off-center shank projecting therefrom, a blade holder comprising complementary parts movable together to clamp the shanks therebetween, and one of the parts having a hub and the other part being provided with movable screw means adapted to be threaded upon the hub for clamping the two parts together.

25. In a rotary oar, a plurality of blades each having an off-center shank with means extending laterally therefrom, a blade holder comprising complementary parts movable together to confine the shanks and laterally extending means therebetween, one of the parts having a threaded hub upon which the other is relatively movable, and the other part having an attached thumb screw threaded upon the hub to relatively move the parts, and stop means at the end of the hub to limit the outward movement of the thumb screw.

30. In a rotary oar, a clamping holder having a pair of relatively movable parts together providing a plurality of radial openings, a plurality of oars each having a blade and an off-center supporting shank together with means extending laterally therefrom, the shank and laterally extending means being insertable in one of the radial openings, and means clamping the parts together to secure the oars immovably to the clamping holder.

35. In a rotary oar, a holder having parts providing a plurality of radially extending peripheral openings, a plurality of oars each having a substantially flat blade and extending from one side thereof a thick shank having a lateral projection adapted for insertion in one of said openings, and means for clamping the parts together to positively lock the oars against movement in the holder.

40. A rotatable oar for boats comprising a wheel having a hub, a plurality of oars each having a reinforcement at one edge terminating in a shank provided with laterally extending means, 75 a clamping plate fitted on the hub having means

for interlocking with each of the oar shanks and lateral means thereon when extended radially from the hub, means for locking the clamping plate on the hub to secure the oars immovably thereto and prevent rotation thereof about the axes of the shanks, and manual operating means for the wheel and oars carried thereby.

15. For use on a boat, an oar wheel having a hub, a mounting on which the wheel is rotatable about an axis transversely of the boat movement through the water, a pivotal support for the mounting parallel with the axis of the oar wheel whereby the mounting is adjustable to vary the submergence depth of the wheel in the water, a manual operator for the wheel comprising a pulley rotatable about the same axis as the pivotal support and spaced from the hub of the oar wheel, and driving means between the pulley and the wheel hub comprising a belt, all of the aforesaid parts constituting an operative assembly attachable to or detachable from the boat as a single unit.

16. For use on a boat, a rotatable oar comprising an oar wheel submersible in the water, a hanger exteriorly of one side of the boat on which the oar wheel is mounted for rotation about an axis transversely of the boat movement through the water, a pivotal support for the hanger including means attachable to the boat at its gunwale permitting the hanger to swing outwardly therefrom to vary the spacing between the oar wheel and the boat, means for locking the hanger in a selected angular position to fix the submergence depth of the wheel in the water, and a manual operator rotatable about an axis coincident with the pivotal support for the hanger for imparting rotation to the wheel in any adjusted position thereof.

17. A rotatable oar comprising a mounting attachable to a boat at its gunwale, an oar wheel submersible in the water and rotatable about an axis transversely of the boat movement through the water, a support upwardly extended from the mounting, a hanger depending from the support, a mounting for the wheel near the lower end of the hanger, pivotal means for adjustably connecting the hanger to the support for swinging movement relative thereto about an axis parallel with that of the oar wheel whereby to vary the submergence depth of the wheel in the water, means for locking the hanger in a selected angular position with respect to the support, and a manual operator fixed to the hanger coaxially of the pivotal connecting means therefor for rotating the wheel in any angular position relative to the support.

18. A rotatable oar comprising a vertically extending support attachable to a boat at its gunwale, an oar wheel submersible in the water and rotatable about an axis transversely of the boat movement through the water, a hanger for mounting the oar wheel, a pivotal connection between the hanger and the support, means for adjustably swinging the hanger with respect to the support to raise and lower the wheel, means for setting the hanger in a selected angular position with respect to the support, and a manual operator fixed to the hanger coaxially of its pivotal connection with the support for rotating the wheel in any adjusted position relative to the support, all of the aforesaid parts constituting an operative assembly attachable to or detachable from the boat as a single unit.

19. For use on a boat, a knock-down rotary oar comprising a gunwale clamp, supporting means connected to the clamp and depending below the gunwale, dual pivotal mountings comprised in the supporting means permitting the latter to swing about transverse axes to different positions of adjustment, a submersible oar wheel carried by the supporting means at a selected point below the gunwale and mounted for rotation about a substantially horizontal axis transversely of the boat movement through the water, and manual operating means including a crank mounted on the supporting means for movement about an axis coincident with one pivotal mounting comprised in the supporting means and parallel with the axis of the oar wheel in operative connection with the oar wheel for transmitting motion thereto, all of the aforesaid parts constituting an operative assembly attachable to or detachable from the boat as a single unit.
